FIG. 10

FIG. 6

FIG. 11

FIGURE 1 is a perspective view of a surfboard bumper showing my new design;

FIGURE 2 is a top plan view thereof;

FIGURE 3 is a rear elevational view thereof;

FIGURE 4 is a bottom plan view thereof;

FIGURE 5 is a front elevational view thereof;

FIGURE 6 is a side elevational view looking in the direction of the arrow 6 of FIGURE 5;

FIGURE 7 is a top plan view of a modified embodiment of a surfboard bumper showing my new design;

FIGURE 8 is a rear elevational view thereof;

FIGURE 9 is a bottom plan view thereof;

FIGURE 10 is a cross section taken in the direction of the arrows 10—10 of FIGURE 3 of my first-mentioned design; and

FIGURE 11 is a cross section taken in the direction of the arrows 11—11 of FIGURE 8 of my modified design.

The broken lines of a surfboard shown in FIGURE 1 are for illustrative purposes only. Front and side eleva-

tional views of my modified design correspond to FIGURES 5 and 6 respectively of my first-mentioned design.

This application is a continuation-in-part of my co-pending application Ser. No. D. 6,533 filed Apr. 5, 1967, and now abandoned.

I claim:

The ornamental design for a surfboard bumper, substantially as shown and described.
